DESIGN FOR A CHAIR OR SIMILAR ARTICLE

Elmer R. Luger, Anoka, Minn.

Application September 5, 1939, Serial No. 87,054

Term of patent 7 years

To all whom it may concern:

Be it known that I, Elmer R. Luger, a citizen of the United States and residing in the city of Anoka, county of Anoka, and State of Minnesota, have invented a new, original, and ornamental Design for a Chair or Similar Article, of which the following is a specification, reference being had to the accompanying drawing, forming a part thereof, wherein the single figure in the drawing is a perspective view of a chair showing my new design.

The dominant features of my design reside in the portions shown in solid black lines in the drawing.

I claim:

The ornamental design for a chair or similar article, as shown and described.

ELMER R. LUGER.
